UNITED STATES PATENT OFFICE

164,650

STAND FOR HEATED FOOD RECEPTACLES

Daniel C. O'Connell, Bedford Village, N. Y., assignor to Sterno, Inc., New York, N. Y., a corporation of New York

Continuation of design application Serial No. 6,449, December 6, 1949. This application April 26, 1950, Serial No. 9,489

Term of patent 14 years

(Cl. D44—10)

To all whom it may concern:

Be it known that I, Daniel C. O'Connell, a citizen of the United States, residing at Bedford Village in the county of Westchester, State of New York, have invented a new, original, and ornamental Design for a Stand for Heated Food Receptacles, of which the following is a specification, reference being had to the accompanying drawing, forming part thereof, in which:

Fig. 1 is a perspective view of a stand for heated food receptacles embodying my new design;

Fig. 2 is a front elevational view; and

Fig. 3 is a top plan view thereof.

This application is a continuation of my co-pending design patent application Serial No. D. 6,449, filed December 6, 1949, now abandoned.

I claim:

The ornamental design for a stand for heated food receptacles, as shown.

DANIEL C. O'CONNELL.
